(57) **CLAIM**

The ornamental design for a putter head, as shown and described.

DESCRIPTION

The antennae are intended for ornamental purposes. The ball at the end of the antennae optionally displays a slight circular marking to enhance the overall snail-like appearance of the putter head.

FIG. 1 is a rear perspective view of the putter head;

FIG. 2 is a front perspective view thereof;

FIG. 3 is a front perspective view of a second embodiment of the putter head as disclosed in FIG. 1;

FIG. 4 is a rear perspective view of FIG. 3; and,

FIG. 5 is a front perspective view of a third embodiment of the putter head as disclosed in FIG. 1.

The undisclosed sides of the third embodiment are identical to that disclosed in the first and second embodiments.

The broken line showing is for illustrative purposes only and forms no part of the claimed design.
